Attn:

UNITED STATES PATENT OFFICE.

JAMES S. McMURTRY, OF ST. LOUIS, MISSOURI, ASSIGNOR OF TWO-THIRDS TO MARCUS T. MILONA AND WILLIAM H. F. HARVEY, BOTH OF SAME PLACE.

DUMPING-WAGON.

SPECIFICATION forming part of Letters Patent No. 319,739, dated June 9, 1885.

Application filed November 17, 1884. (No model.)

To all whom it may concern:

Be it known that I, JAMES S. McMURTRY, of the city of St. Louis, in the State of Missouri, have invented a certain new and useful Improvement in Dumping-Wagons, of which the following is a full, clear, and exact description, reference being had to the accompanying drawings, forming part of this specification.

10 Figure 1 is a side view with the body in discharging position. Fig. 2 is a top view with half of the body omitted. Fig. 3 is a longitudinal section, parts being shown in side view. Fig. 4 is a detail transverse section at 15 4 4, Fig. 3.

The fore wheels are shown at A, and the hind wheels at B.

C is the fore axle, and D the hind axle.

20 E F is a bolster resting on the fore axle and connected with it by the king-bolt G, as usual, allowing the axle to turn beneath the bolster.

H is a reach connecting the bolster E F with the hind axle, and the bolster I thereon. This connection may be made by a coupling-25 pole, or in any other suitable manner.

J is a frame supported on the bolsters and inclining downward from the front to the hind end. This frame has side standards, K, forming side guides to the body L. The body 30 has along its bottom rails M, (see Fig. 4,) which run in the circumferential grooves of the wheels N, upon which the body is directly supported, the wheels turning on arbors fixed in the bars of the frame J. Six of these wheels 35 are shown, (three for each rail;) but I do not confine myself to the use of any special number.

O is a cleat attached to the under side or bottom of the body and bearing against the 40 front side of the bolster I to prevent the frame sliding backward. The frame may be secured to the bolsters E F and I in any suitable manner. There are upturned hooks P, secured to the cleat O, to arrest the backward 45 movement of the body along the frame, the hooks engaging a cross-bar, Q, secured to a projection, Q, at the bottom of the body. The hooks and bar form the hinge on which

the body tilts backward when dumping its load.

50 R R are plates having a space, R', between each pair, through which the cross-bar is inserted. The cross-bar slides under the plates, and the latter prevents the tilting of the body before it reaches the proper position.

To prevent the body tilting over too far, there are arms S, pivoted at s to the sides of the frame J, and extending between the sides of the body and strips or cleats T, fastened at the ends to the body. The arms have at the 60 free ends heads S', too large to pass through the slot between the body and cleat T, the upper edge of the body coming in contact with the head when the body has tilted back to a certain degree.

65 To give means for drawing the body forward on the frame into its loading position, a chain or cord, U, is attached to the bottom of the body and carried around a windlass, V, at the front of the frame. The windlass may 70 be turned by a hand-crank, W, either upon the windlass-shaft or connected therewith by cog-gearing.

X is a cog-wheel upon the windlass, and Y is a dog, which may be turned either into or 75 out of engagement with the cogs of the wheel, so as to prevent the rotation of the windlass. This dog is more especially used when the body is drawn up to its loading position to hold it in such position by preventing the 80 uncoiling of the rope or chain U from the windlass.

It will be seen that the rails M and the grooved wheels on which they work form 85 very effective guides to the body in running upon the frame, and that the standards K serve to guide the body when being tilted, and to prevent the rails being thrown out of the wheel-grooves by violent jars, &c.

The upper portion, F, of the fore bolster 90 may be attached to the lower portion, E, or may be attached to the frame J. In the latter case the frame may be set upon the ordinary running-gears of a wagon, and will have the necessary inclination, as the bolster E sets 95 upon the front bolster of the same.

I claim—

1. In a dumping-wagon, the combination, with the running gear, of a body or box provided with rails M and projection Q, carrying 5 a cross-bar, Q', and the frame J, having grooved rollers N, upturned hooks P, and guard-plates R, leaving openings R' between them, and means for retaining the body or box in normal condition.

10 2. In a dumping-wagon, the combination,

with the running-gear and supporting frame, of the body having cleats or strips T, and the arms S, pivoted to the frame, extending between the cleats and the body, and provided with heads S' at their free ends.

JAMES S. McMURTRY.
